INVENTOR.
Edward Little
BY
Horatio E. Bellows
ATTORNEY

UNITED STATES PATENT OFFICE.

EDWARD LITTLE, OF PAWTUCKET, RHODE ISLAND.

CURTAIN FIXTURE.

Application filed September 30, 1921. Serial No. 504,507.

To all whom it may concern:

Be it known that I, EDWARD LITTLE, a citizen of the United States, residing at Pawtucket, in the county of Providence and 5 State of Rhode Island, have invented certain new and useful Improvements in Curtain Fixtures, of which the following is a specification.

My invention relates to combined shade 10 rollers and curtain brackets or supports.

The essential objects of my invention are adaptability for supporting shades and curtain rods of various lengths; prevention of bending the guide plate or base plate under 15 the action of the attaching screws; the provision against accidental loosening of the shade bracket adjusting means; the provision of a strong adjustable and detachable supporting means for the curtain brackets; 20 and inexpensiveness of construction.

To the above ends essentially my invention consists in such parts and in such combinations of parts as fall within the scope of the appended claims.

25 In the accompanying drawings which form a part of this specification,

Figure 1 is a front elevation of the upper portion of a window casement to which my device is applied,

30 Figures 2 and 3, front and rear perspective views of the latter,

Figures 4 and 5, sections of the same on lines 4—4 and 5—5 respectively of Figure 2,

35 Figure 6, a detail view of the adjusting screw, and

Figure 7, a detail view of a slidable member.

Like reference characters indicate like 40 parts throughout the views.

In the drawings 8 is the window casing on each side of which is a bracket represented in a general way by 9. Each bracket comprises an elongated guide plate 11 provided with a longitudinal guide slot 12 and holes 14 adjacent its four corners to accommodate attaching screws 15. The material of the plate 11 at its ends is bent rearwardly 45 to form end walls 17, and then rearwardly to form rear walls 18 parallel with the plate 11 provided with centrally extended portions 19 provided with forwardly directed lateral flanges 20 abutting against the guide plate adjacent and between each pair of

holes 14. The portions 18, 19, and 20 thus 55 form such a reinforcement that the attaching screws 15 may be tightly engaged in the window casing through the holes 14 without bending the guide plate 11.

Means for supporting shade rollers consists of a slidable plate 22 provided upon its ends with guide fingers or flanges 24 loosely engaging the upper and lower edges of the plate 11. Integral with the lateral edge of the slidable plate is an ear 26 disposed at right angles to the plane of the plate having upper and lower lugs 28; one horizontal and the other depending, provided respectively with perforations 29 and 30 for the reception of the ends of an upper 60 and a lower shade roller.

For adjustment the plate 22 has a hole 32 to admit an adjusting screw 34 which passes through the slot 12 and has a head 36 abutting against the rear of the plate 11 and provided with a guide rib 37 slidable in the slot. A milled nut 38 engages the screw in front of the plate 11. The ear 26 is cut away at its base to form a cavity 40 which affords access to the nut 38 while the ear it- 70 self forms a guard for the latter.

A curtain rod support comprises a supporting rod or arm 42 provided preferably with a downward bend 45 and a terminal upturned end portion 44. The inner end of the arm has a depending closed loop 46 constituting a brace. The material of the loop is at its end downwardly bent as at 48 forming a resilient terminal finger 50. The bend or loop 48 receives the upper margin 90 of the plate 11 against the rear face of which the finger 50 bears. The construction of the brace 46 and its integral resilient finger 50 facilitates the changing of the arm 42 to any desired location on the guide plate required by the length of the curtain rod supported or engaged by the arm. In Figure 4 is shown in broken lines one of several possible adjusted positions which may be assumed by both the shade and curtain rod 95 supports.

I claim:

1. In a device of the character set forth, a guide plate provided with marginal screw holes, a shade support mounted on the plate, rearwardly directed walls formed on the ends of the plate, rear walls integral with the end walls comprising reduced end 105

portions, lateral forwardly directed flanges on the reduced portions of the rear walls engaging the plate adjacent the screw holes.

2. In a device of the character described, a guide plate provided with a guide slot, a shade support comprising a slidable plate, flanges on the second plate embracing the

first plate, and an ear on the slidable plate provided with a cavity, a clamping screw in the slidable plate and guide slot, and a ¹⁰ thumb nut on the screw within the cavity.

In testimony whereof I have affixed my signature.

EDWARD LITTLE.
